United States Patent Office

Des. 195,877
Patented Aug. 6, 1963

195,877

LAMP BASE OR SIMILAR ARTICLE

Alice Welpley, Leland C. Welpley, and Bruce W. Welpley, all of 1310 Whitnall Highway, Burbank, Calif.

Filed June 21, 1962, Ser. No. 70,639

Term of patent 14 years

(Cl. D48—20)

FIGURE 1 is a side elevational view of a lamp base or similar article showing our new design, wherein all sides are substantially the same in appearance and the outline of a shade is shown in dotted lines for illustrative purposes only.

We claim:

The ornamental design for a lamp base or similar article, as shown and described.
